ENGINE STARTING MECHANISM

Arthur E. Raabe, Summit, N. J., assignor to
 Eclipse Aviation Corporation, East Orange,
 N. J., a corporation of New Jersey

Application March 6, 1931, Serial No. 520,633

6 Claims. (CL 123—179)

This invention relates to engine starters, and more particularly to starters of the type wherein the engine engaging member is rotated by a variable speed driving member.

5 In engine starters of this type, as for example, inertia starters wherein the energy stored in a rapidly rotating flywheel is applied to an engine engaging member for cranking purposes, it is desirable that the latter member be rotated at 10 a substantially constant speed during the major portion of the cranking operation. In apparatus of this kind heretofore known such a condition has been impossible of achievement since, with the known forms of transmissions between the 15 variable speed driving member or flywheel and the engine engaging member, the speed of rotation of the latter member continuously varies in proportion to the changes in speed of the former. Consequently, if the engine does not start within 20 the first few seconds of cranking, during which time the speed of the flywheel is relatively high, the ensuing decrease in cranking speed, due to the slowing down of the flywheel, usually renders the cranking effort insufficient for starting purposes, 25 and necessitates another cranking operation.

It is therefore one of the objects of the present invention to provide an engine starter wherein the cranking speed is maintained substantially constant during the major portion of the cranking operation.

Another object is to provide novel engine starting mechanism wherein the speed of rotation of an engine engaging member is maintained substantially constant irrespective of changes in 30 speed of the means for driving said member.

A further object is to provide an engine starter of the inertia type embodying novel transmission means between the inertia member and the engine engaging member whereby the driving ratio 40 of said means is varied in accordance with changes in the speed of rotation of the inertia member.

Still another object is to provide engine starting apparatus of the type wherein an engine engaging member is rotated by a variable speed 45 driving member which embodies novel means for varying the ratio between the speeds of rotation of said members in accordance with variations in speed of the driving member.

A still further object is to provide an engine 50 starter of the inertia type which embodies novel motion transmission means between the inertia member and its energizing cranking shaft whereby the inertia member is accelerated first more slowly, and then more quickly, than said cranking shaft.

These and other objects will appear more fully from a consideration of the detailed description of the invention which follows. Although only one embodiment of the invention is described and illustrated in the accompanying drawings, it is to be expressly understood that these drawings are for the purpose of illustration only and are not to be construed as a limitation of the scope of the invention, reference being had for this purpose to the appended claims.

Referring now to the drawings, Fig. 1 of which is a sectional side view with certain parts shown in full, and Fig. 2 is an end view of the friction rollers of the drive of one embodiment of the present invention, there is disclosed therein a 10 hand actuated starter of the inertia type which is provided with novel means for automatically varying the driving ratio between the inertia member and the engine engaging member and the hand cranking shaft in accordance with changes in the speed of rotation of the former. In the form shown, the starting mechanism 15 comprises a flywheel 2 adapted to rotatably drive an engine engaging member or clutch jaw 3 which is movable into driving engagement with a corresponding jaw member (not shown) provided on the crank shaft or crank shaft extension of the engine to be started. The mechanism is housed within a suitable casing constituted by an inner section 4, a pair of intermediate sections 5 and 6, and a flywheel cover section 7, the sections being removably secured together in any suitable manner and the inner section being provided with a flange 8 to facilitate the mounting of the starter on the engine crank 20 case, or in any other suitable location.

The flywheel is adapted to be rotated at high speed in order that sufficient energy may be stored therein for cranking the engine, and a gear train is preferably provided for transmitting the energy stored in the flywheel to the engine engaging member 3, said gear train being so constituted that member 3 will be rotated at a much lower speed than the flywheel, and embodying novel driving-ratio changing means which are adapted to be automatically actuated according to the variations in speed of rotation of the flywheel. As shown, flywheel 2 is mounted on a shaft 9, the outer end of which is suitably journalled as by a ball bearing 10 in a boss 11 formed centrally of flywheel cover section 7 of the starter casing, the outer end of said boss being closed by a suitable cover plate 12 removable to allow access to the mechanism for adjustment purposes. The inner race of ball bearing 10 is maintained in 30 35 40 45 50 55

its proper position on flywheel shaft 9 abutting the hub of flywheel 2 by means of a suitable slotted nut 13, while the outer race of said bearing has a sliding fit within a liner 14 which is provided within the bore of boss 11.

Flywheel 2 is provided intermediate its hub and rim with a plurality of circumferentially spaced holes 15 adapted to receive pins 16 which are carried by a plate 17, the latter forming one element of the novel ratio changing device which is interposed in the transmission between flywheel 2 and engine engaging member 3. Pins 16 are adapted to slide freely through holes 15 in flywheel 2, thereby allowing relative axial movement between said flywheel and plate at the same time that they are constrained to rotate in unison. Plate 17 is freely mounted on a sleeve 18 which in turn is slidably mounted on shaft 9 for a purpose later to be described.

The inner face of plate 17 has frictional engagement with the surfaces of a plurality of barrel shaped rollers 19, preferably three in number. Rollers 19 are rotatably mounted as by suitable bearings 20 on spindle shafts 21 carried in yokes 22, said yokes being free to oscillate about trunnions 23 which are rotatably supported in suitable bosses 24 formed in a cage or yoke 25 integral with sections 6 and 7 of the starter housing. In frictional contact with the diametrically opposite portions of the surfaces of rollers 19 is a second plate 26 having a hub portion 27 in which is housed a combined thrust and friction bearing 28 the inner race of which surrounds and supports the inner end of flywheel shaft 9 and abuts an enlarged head 29 formed thereon.

It will be seen from the structure thus far described, that the rotation of flywheel 2 is transmitted through pins 16 to plate 17 and thence through rollers 19 to plate 26. In the position shown in the drawings, the circles of contact between plate 17 and roller 19 on the one hand, and between rollers 19 and plates 26 on the other, have radii of equal length, and it is evident that flywheel 2, plate 17 and plate 26 would all have the same speed of rotation.

The inner portion of hub 27 of plate 26 is slidably but non-rotatively mounted as by splines 30 on a collar member 31 which is secured to a stub shaft 32 by splines 33 and a screw threaded in shaft 32, the head of which is shown at 34. Shaft 32 is rotatably supported as by ball bearings 35 in a central opening in a wall 36 formed integrally with intermediate section 5 of the starter casing. The inner end of stub shaft 32 is provided with a pinion 37 which meshes with a spur gear 38 formed on the large end of a bell shaped member 39 rotatably mounted as by means of a stub shaft 40 and bearings 41 in an elongated boss 42 formed in wall 36. Formed integrally with bell shaped member 39 and shaft 40, or rigidly connected thereto in any suitable manner, is a pinion 43 which meshes with an internal spur gear 44 coaxially disposed with respect to flywheel 2. Internal spur gear 44 is provided with a hub 45 which is rotatably mounted on a stub shaft 47 formed integrally with, and projecting centrally from, the closed end of a barrel 48 rotatably mounted in inner housing section 4 by means of ball bearings 49.

Hub 45 of internal spur gear 44 is also provided with an integrally formed pinion 50 which constitutes the sun gear for a plurality of planetary gears 51, one of which is shown in section 75 in the drawings. These planetary gears 51, of

which three are preferably employed, spaced at intervals of 120° about the closed end of barrel 48, mesh with an internal ring gear 52 which is rigidly secured in any suitable manner to the inner surface of housing section 4. Each planetary gear is rotatably mounted as by a bearing 53 on a sleeve 54 the inner end of which is countersunk in the outer face of the closed end of barrel 48 and through which extends a screw 55 threaded into the end of said barrel. A retaining ring 56 is carried by the outer ends of screws 55 and maintains bearings 53 in their proper position on sleeves 54.

Means are preferably interposed between the transmission gear train above described and the engine engaging member 3 for yieldingly transmitting the energy from the flywheel to the engine crank shaft without damage to the parts such as might result if the driving connections were entirely constituted by rigidly connected elements. For this purpose, a multiple disc clutch is preferably employed, said clutch being mounted within barrel 48.

As shown, the clutch comprises a plurality of annular discs 57 which are alternately splined to the inner surface of barrel 48 and to the outer surface of an interiorly threaded nut 58, and positioned between a flange 59 formed on the outer surface of nut 58 intermediate its ends and the closed end of barrel 48. Suitable adjustable yielding means are also provided for holding nut 58 in operative position with respect to discs 57 and barrel 48, and for varying the frictional engagement of said discs. In the form shown, the yielding means comprise a plurality of coil springs 60 extending longitudinally within the barrel with their outer ends having operative engagement with flange 59 and their inner ends exerting a thrust against an annular ring 61 mounted within the barrel and provided with a plurality of laterally projecting studs 62 which extend into the coils of springs 60 thereby maintaining them in proper spaced relation within the barrel. An adjusting nut 63 is threaded into the open end of the barrel and has abutting engagement with the inner face of ring 61. By adjusting the position of nut 63 longitudinally of barrel 48 the compression of springs 60 may be changed to vary the pressure with which the clutch discs 57 are engaged.

Exteriorly threaded onto the inner end of barrel 48 is a retaining ring 64 for the adjacent bearing 49. Ring 64 may be locked in position by means of a wire 65 one end of which passes through said ring and engages one of a plurality of longitudinal slots 66 formed in the inner end of barrel 48, said ring being adapted to coact with a shoulder formed on the outer end of the barrel and having engagement with the inner race of outer bearing 49, to prevent endwise movement of the barrel relative to inner housing section 4.

Positioned within nut 58 is an exteriorly threaded shaft 68 adapted for rotary and longitudinal movement relative to said nut. The outer end of said shaft is provided with suitable means such as a nut 69 adapted to engage a shoulder formed interiorly of nut 58 to limit longitudinal movement of the shaft to the left, as viewed in the drawings. The inner end of shaft 68 is longitudinally splined and extends into the correspondingly splined hub portion 70 of engine engaging member 3 whereby these parts have positive driving engagement, but are also adapted for relative longitudinal movement. A 75

coil spring 71 which preferably has its outer end extending into a recess formed in the inner end of shaft 68 is interposed between said shaft and the outer face of engine engaging member 3, and 5 yieldingly resists movement of said member toward the shaft.

Suitable manually operable means are preferably provided for rotating flywheel 2 in order to store energy therein. As shown, said manually 10 operable means include a cranking shaft 72 which is rotatably mounted in intermediate housing section 5 with the outer end thereof projecting exteriorly of said housing and provided with suitable means such as a transverse pin 73 for receiving an ordinary hand crank (not shown). Shaft 72 is rotatably supported in the plane of the side wall of section 5 by means of a ball bearing 74, while the inner end of said shaft, which extends substantially at right angles to the axis 15 of rotation of flywheel 2, is rotatably supported in a boss 75 provided in wall 36 by means of a roller bearing 76. The inner end of shaft 72 has rigidly connected thereto a bevel gear 77 which meshes with a similar bevel gear 78 drivably connected to the outer end of stub shaft 47, and spaced from the hub 45 by a suitable washer 78a.

Suitable means are also provided for moving engine engaging member or clutch jaw 3 into engagement with a corresponding member (not 20 shown) mounted on the engine crank shaft whereby the energy stored in flywheel 2 is effective to crank the engine. In the form shown, said means comprises a rod 79 which slidably extends through stub shaft 47, threaded shaft 68, 25 and a central opening in engine engaging member 3. The inner end of rod 79 carries a nut 80 which engages the inner face of clutch jaw 3 and maintains the latter in operative position relative to threaded shaft 68. The inner portion 30 of rod 79 is of reduced diameter to provide a shoulder 81 which normally engages the outer end of shaft 68. The outer end of rod 79 terminates closely adjacent pinion 37, and is pivotally connected to the bifurcated end 82 of an operating lever which extends through the starter housing and is provided with suitable means for manual 35 actuation by the operator.

Means are preferably provided for preventing oil from seeping from the engine crank case into 40 the starter housing, since such oil would impair the operation of the apparatus. For this purpose, a cup-shaped member 83, which is preferably formed of metal and provided on its outer end with a flange 84 adapted to be clamped between 45 flange 8 of the starter housing and the crank case of the engine, is fitted over the inner end of the starter which projects into the crank case. Secured to the member 83 is a flexible guard or disc 50 85 of annular form, the inner periphery of said guard having engagement with the outer surface of the laterally projecting hub portion 70 of the engine engaging member 3. A sleeve 86 surrounds and has sliding engagement with hub portion 70 and extends inwardly into abutting engagement 55 with flange 59. The inner end of sleeve 86 bears against a ring 87 to hold the latter in engagement with flexible guard 85. The length of sleeve 86 is preferably such that the inner portion of guard 85 is flexed outwardly into engagement with the adjacent face of engine engaging member 3, and 60 seepage of oil into the starter casing at this point is thereby prevented without interference with the longitudinal movement of the engine engaging member. A pair of washers 88, one of which 65 may be formed of flexible material, is mounted on

rod 79 intermediate spring 71 and engine engaging member 3 to prevent seepage of oil through the central opening in said member.

With the structure thus far described, energy 5 may be stored in flywheel 2, preparatory to cranking the engine, by engaging a hand crank with the outer end of cranking shaft 72 and rotating the latter. This motion is transmitted through the gear train to plate 26, and thence through rollers 19, plate 17, and pins 16 to flywheel 2 10 15 whereby the latter is rotated a large number of times for each revolution of cranking shaft 72. Actuation of shaft 72 also results in rotation of barrel 48 and all the parts therein with the exception of rod 79 which maintains engine engaging member 3 out of driving engagement with the engine member. After the flywheel has been brought to the desired speed of rotation, i. e., after sufficient energy for cranking the engine 20 has been stored therein, the operator actuates the lever having the bifurcated end 82 whereupon rod 79 is forced to the left, as viewed in the drawings. Shoulder 81 forces shaft 68 to the left, the latter having a combined rotary and longitudinal movement due to its threaded connection with 25 the nut 58, and engine engaging member 3 is drivably moved, through spring 71, into full meshing engagement with the engine member. The energy of the flywheel is now effective to 30 crank the engine.

When the engine starts under its own power the speed of rotation of the engine clutch jaw is greater than that of engine engaging clutch jaw 3, and the inclined teeth of said jaw members are now effective to move member 3 to the 35 right out of driving engagement.

With this structure, however, the speed of rotation of the engine engaging member 3 is always proportionate to the speed of rotation of flywheel 2. Also, when storing energy in the flywheel preparatory to cranking the engine, the acceleration which can be imparted to the flywheel during this operation depends directly upon the acceleration of cranking shaft 72. To overcome these disadvantages inherent to starters of this type employing a fixed-ratio gear train, novel means have been provided whereby, in effect, the multiplying factor of the transmission means drivably connecting flywheel 2 and engine engaging member 3, and cranking shaft 72, may be automatically varied 40 45 in accordance with changes in the speed of rotation of the flywheel so that the speed of the engine engaging member may be maintained substantially constant during the major portion of the cranking operation, and the flywheel may be 50 55 more rapidly accelerated during the energy storing operation.

In the form shown, plate 17 is provided with a plurality of circumferentially spaced bosses 89 in each of which is pivoted, intermediate its ends, a 55 lever 90 weighted at its outer end and of such shape as to be oscillatable about its pivot under the action of centrifugal force. The inner ends of levers 90 operatively engage a collar or washer 91 mounted on sleeve 18 and adjustable in longitudinal position thereon as by a nut 92 threaded onto the outer end of said sleeve. The inner end of sleeve 18 is provided with a suitable thrust bearing 93 and a thrust ring 94 between which are held the inwardly projecting ends 95 of spindle shafts 21 70 75 of rollers 19. Suitable resilient means such as coil springs 96 are interposed between thrust ring 94 and the central portion of plate 17, and resist the movement of sleeve 18 and inner ends 95 of spindle shafts 21 to the right under the action of centrif- 75

initial force exerted on weighted levers 90. The initial compression of springs 96 can be adjusted by means of nut 92.

The operation of this novel ratio changing device is as follows: Spring 96 normally holds projecting ends 95 of the spindle shafts 21 to the left of the position shown in the drawings, thereby cocking the rollers 19 so that upon initiation of the energy storing operation by manual operation of shaft 72, the drive from plate 26 to plate 17 is such as to cause the latter to rotate more slowly than the former. As flywheel 2 accelerates, however, the weighted ends of levers 90 move outward under the action of centrifugal force and rotate said levers about their pivots in bosses 89, causing the inner ends to press against collar 91 and thereby move sleeve 18 to the right, as viewed in the drawings, against the resistance of springs 96. The motion of sleeve 18 in turn carries projecting ends 95 of spindle shafts 21 to the right and oscillates yokes 22 about their trunnions 23, thereby causing the rollers 19 to return first to the vertical position and from such position to move into the opposite inclined position. This movement causes a change in the loci of the frictional engagement circles on plates 26 and 17, thereby changing the driving ratio so that the latter rotates faster than the former. Hence, as the cranking operation proceeds, the inertia member 30 is accelerated first more slowly and then more quickly than the cranking shaft 72. As shown in the drawings, an increase from the angle of cocking of rollers 19 causes plate 17 to rotate faster than plate 26.

35 Since cocking of rollers 19 causes the distance between plates 17 and 26 to increase slightly, suitable means are provided for allowing relative movement of the parts involved and for returning said parts to their original positions when the 40 angle of tilt of the rollers is reduced. As previously mentioned, pins 16 are freely slideable through holes 15 in flywheel 2, thereby allowing relative axial movement between plate 17 and flywheel 2, while the splined engagement at 30 between hub 45 27 of plate 26 and collar member 31 of stub shaft 32 permits similar movement between these parts. To maintain plates 17 and 26 in frictional engagement with the surfaces of rollers 19, and to 50 resiliently urge said plates toward their at-rest positions, suitable resilient means are provided such as a plurality of coil springs 91 encircling pins 16 between the inner face of flywheel 2 and the outer face of plate 17.

When flywheel 2 has been accelerated to its 55 maximum or proper driving speed for starting the engine, rollers 19 are in the position of maximum cocking or tilt and the speed reduction ratio from plate 17 to plate 26 is a maximum. Engine engaging member 3 may be now moved into engagement with the engine member to be started, and the engine is cranked by the application of the energy stored in flywheel 2. As this cranking operation progresses, the speed of rotation of flywheel 2 decreases, and were there provided only 60 the usual fixed-ratio transmission gear train between said flywheel and engine engaging member 3, the speed of the latter would be decreased in proportion. However, due to the movement of weighted lever arms 90 in response to variations 65 in centrifugal force, the degree of tilt of rollers 19 is decreased with a decrease in speed of rotation of flywheel 2, with a consequent decrease in the speed reduction ratio between plate 17 and plate 26.

70 The result of this operation is that the speeds of plate 26 and engine engaging member 3 re-

main substantially the same as they were at the instant of initial engagement of the latter with the engine.

There is thus provided by the present invention a novel engine starter wherein the speed of rotation of the engine engaging member is maintained substantially constant during the major portion of the engine cranking operation irrespective of variations in the speed of the driving member from which the engine engaging member derives its energy. Novel transmission means have been provided for driving an engine engaging member from a variable speed member, such as a flywheel, whereby the driving ratio is automatically varied in accordance with changes in the speed of rotation of the driving member. When applied to a hand energized inertia starter, the invention also permits more rapid acceleration of the inertia member to its maximum or designed operative speed than would be possible with a fixed ratio set of gearing. Since the speed of rotation of the engine engaging member is thus maintained substantially constant, torque conditions are also proportionately better and the starter is made more efficient in operation.

It will be obvious that the invention is not limited to the form shown in the drawings, but is capable of a variety of mechanical embodiments. For example, any suitable type of variable speed driving means may be substituted for the inertia flywheel shown. Also, the manual cranking means may be replaced or supplemented by suitable electrical means, and other forms of gearing and yieldable driving connections may 35 obviously be employed in place of those illustrated. Various other changes, which will now appear to those skilled in the art, may be made in the form, details of construction and arrangement of the parts without departing from the 40 spirit of the invention, and reference is therefore to be had to the appended claims for a definition of the limits of the invention.

What is claimed is:

1. In an engine starter, an engine engaging member, a variable speed driving member, means including a pair of parallel plates rotatable about a common axis to drivably connect said driving member and said engine engaging member, and centrifugally actuated means for imparting relative axial movement to said plates to automatically change the driving ratio in accordance with the speed of the driving member.

2. Driving means for an engine starting member comprising an inertia member in which energy is stored for subsequent transmission to said engine starting member, and means operating in response to variations in the speed of said inertia member to maintain said engine starting member in rotation at substantially constant speed.

3. Driving means for an engine starting member comprising an inertia member in which energy is stored for subsequent transmission to said engine starting member, and means operating in response to variations in the speed of said inertia member to maintain said engine starting member in rotation at substantially constant speed said maintaining means comprising a pair of parallel plates rotatable about a common axis, and means for imparting relative axial movement to said plates to maintain the speed of the driven plate substantially constant irrespective of changes in the speed of the driving plate.

4. Driving means for an engine starting member comprising an inertia member in which

energy is stored for subsequent transmission to said engine starting member, and means operating in response to variations in the speed of said inertia member to maintain said engine starting member in rotation at substantially constant speed said maintaining means comprising a pair of parallel plates rotatable about a common axis for driving said engine engaging member, and means for imparting relative axial movement to said plates to automatically vary the driving ratio between said last named means and said engine engaging member in accordance with changes in the speed of said driving means.

5. Driving means for an engine starting member comprising an inertia member in which energy is stored for subsequent transmission to said engine starting member, and means operating in response to variations in the speed of said inertia member to maintain said engine starting member in rotation at substantially constant speed said maintaining means comprising a pair of parallel plates rotatable about a common axis to drivably connect said driving member and said

engine engaging member and centrifugally actuated means for imparting relative axial movement to said plates to automatically change the driving ratio in accordance with the speed of the driving member.

6. Driving means for an engine starting member comprising an inertia member in which energy is stored for subsequent transmission to said engine starting member, and means operating in response to variations in the speed of said inertia member to maintain said engine starting member in rotation at substantially constant speed said maintaining means comprising a pair of plates having parallel friction surfaces, and a roller engaging said friction surface along a single circle of contact when the distance between said opposing friction surface is smallest, and along separate circles of contact with respect to each of said surfaces in the event of an increase in the distance between said opposing friction surfaces due to a change in the rotary speed of said driving member.

ARTHUR E. RAABE.
